WATER DETECTOR FOR OIL WELLS

Raymond S. Hunt, Mount Pleasant, Mich.

Application April 4, 1945, Serial No. 586,511

4 Claims. (Cl. 166—1)

1

This invention relates to a water detector for oil wells.

In drilling wells for oil, the hole drilled downward through the earth frequently goes through a water bearing stratum whereupon the hole or passage is filled with water. Upon this occurring and after a solid rock stratum has been reached, it is customary to drive a casing down and attempt to provide a seal between the casing and the solid seat against which it engages, thereafter continuing drilling with a smaller diameter hole or passage. In such drilling beyond the casing and seal, frequently more water appears and previously there has been no way of knowing whether such additional water came from a new water bearing stratum which had been opened or whether the seal has been broken permitting inflow of water from the first source.

It is a primary object and purpose of the present invention to provide a novel detector means, which is a carrier or container for dye, for coloring water from the first source of water which has been passed through, and which will give, to any water coming from the first water bearing stratum, a distinctive color whereby upon further drilling beyond the lower end of the casing and its seal water thereafter encountered, if it is colorless, will be known to have come from a new water bearing stratum below the casing. On the contrary if the water is colored, it is then known that it is water from the first water bearing stratum which was drilled through, and which has escaped from the drilled hole or passage and thence into the casing because of leakage due to ineffectiveness or rupture for any reason of the seal described.

A further object of the invention is to provide such container or carrier for the dye and safeguard it so that the mixture of dye with water from the first water bearing stratum in the drilled passage or hole will not occur until after the casing has been introduced and has been moved downwardly the full length of the drilled passage and seated and sealed at its lower end, whereby the distinctive color given to the water will not manifest itself and show up too early and, therefore, defeat the purpose for which it is to be used.

The invention for the attainment of the objects stated, and for others which will be hereafter enumerated, may be understood from the following description taken in connection with the accompanying drawing, in which,

Fig. 1 is a section and elevation illustrative of strata passed through in drilling an oil well and

2

with the well cased and my invention utilized in connection therewith.

Fig. 2 is a horizontal section, enlarged substantially on the plane of line 2—2 of Fig. 1, looking in a downward direction.

Fig. 3 is a transverse section substantially on the plane of line 3—3 of Fig. 2, and

Fig. 4 is a section similar to Fig. 3, fragmentary only, at one side of the dye carrying member.

Like reference characters refer to like parts in the different figures of the drawing.

Illustrative of a series of strata which may be drilled through in the production of an oil well, in Fig. 1 the upper stratum 1 may be of very considerable thickness and start at the surface of the earth. Below it there may be a water bearing stratum 2 of sand or other porous material, below it a stratum of shale 3 which rests upon limestone stratum 4 and below it the oil bearing stratum 5 may be located. It is of course to be understood that the strata encountered in drilling oil wells are of many and varied characters and what is shown is merely for illustrative purposes.

In the drilling of the well, a downward passage or hole 6 is made through all of the upper strata until the solid rock stratum 4 is reached. In such drilling the water bearing sands at 2 will be passed through and the hole filled with water. When a solid rock foundation is reached as at 4, the drill is pulled and the well cased. In such operation the successive casing sections 7 of pipe are introduced into the well, new sections being successively connected at their lower ends to the upper ends of the sections last introduced, using coupling collars 8 interiorly threaded. The first casing section 7 which is introduced into the well at its entrance or lower end has a sealing sleeve or collar 9 threaded thereon and in usual practice a ring 10 is placed around the lowermost section 7, which for example may be made of a rubber composition and is of an elastic nature, the hope being that it will prevent passage of water below it, but no certainty of such prevention of water passage can be had. The lower end of the sealing collar 9 rests upon the bottom of the drilled hole 6, and because of the weight of the casing, which may be hundreds of

feet in length, will tend to snugly engage the surface and seal off water passage. But such sealing off against water passage cannot be insured and frequently water does pass between the lower end of the seal 9 and the seat against which it is engaged.

With my invention on the lowermost section 7 introduced into the drilled hole or passage 6 a cylindrical sleeve holder and carrier 12 for the dye previously mentioned is mounted, passing over such lower casing section. At its upper end, at a plurality of spaced points around it, upwardly extending pins 13 are provided to insure against the upper end of the sleeve dye carrier 12 abutting against the lower end of the first collar 8 used.

In a preferred form of the sleeve dye carrier, a plurality of holes 14, spaced around the sleeve, are drilled downwardly into the walls of the sleeve but terminate before reaching the lower end thereof. Said holes are partially filled with a crystallin water soluble dye which preferably is mixed with some water effervescent substance which reacts when mixed together in the presence of water with high effervescence. Above such mixture of dye and water effervescent substance a seal 16, which is also water soluble, but slowly so as to take a considerable time, is placed. For example, a hard candy might be used, introduced in liquid form, and allowed to harden.

Such dye carrier sleeve or collar will have the seals at 16 exposed to the action of water, which in general is salt water, and such water soluble seal 16 will slowly dissolve so that eventually the mixture of crystallin dye and water effervescent substance is reached. This provides the time element necessary for casing the well and getting the sealing collar 8 to its lowermost position and seated against the bottom of the drilled hole 6. Such time lag is essential as otherwise the water would become colored and there would be colored water within the casing as well as outside. After the well has been cased, drilling is then continued in a hole or passage 17 or smaller diameter than the drilled hole or passage 6 until either the oil bearing stratum is reached or water is again encountered.

If water appears within the casing upon a continuation of drilling the passage 17 and the water is colored, it is then known that it is not from a fresh or new source of supply but from the same water bearing stratum first encountered. Also if, as occurs at times, the oil bearing stratum is reached and mixed with the oil water appears, and such water is colored, it is thereupon known that there is leakage at the lower end of the seal 8 and that the water does not come from the oil bearing stratum in addition to the oil obtained. But any clear water coming in the succeeding drilling of the smaller passage 17 is necessarily indicative of the fact that an additional source of water supply has been reached.

It is not important at what position, between the lowermost collar 8 and the rubber packer ring 10, that the dye carrying member 12 may be positioned. In any case upon the water soluble sealing material at 16 being dissolved, there is an

effervescence of the water effervescent material 15 with a consequent throwing out of the dye to the water within the hole 6 around the casing and it is dissolved in said water.

It is of course to be understood that there are other ways of insuring the necessary time lag before the dye is reached by the water and to give ample time for completing the casing of the well, many hours at times being required. Nor is the invention restricted to the particular form and type of dye carrying sleeve provided. Many variations in detail of structure may be resorted to for supplying the dye to color the water and for locating and retaining it below the lowermost connecting collar in the casing and for delaying the solution of the dye in the water until the well has been cased. The invention is to be considered comprehensive of all forms of structure coming within the scope of the appended claims which define the invention.

Although this invention has been described as applied to oil wells it is anticipated that it may also be used in other wells such as gas wells.

I claim:

1. A structure as described comprising, a sleeve open at both ends through which a lowermost section of a casing of an oil well is adapted to be passed, said sleeve having a cavity formed between the inner and outer sides of the sleeve, water soluble dye partially filling said cavity, and a seal of material which dissolves slowly in water closing said cavity adjacent its upper end.

2. A construction as defined in claim 1, said sleeve around it being provided with a plurality of said cavities spaced from each other, each open at its upper end, filled with water soluble dye and sealed adjacent its upper end with a water soluble seal of slowly dissolving material.

3. A construction as defined in claim 1, and a plurality of spaced apart projections extending upwardly from the upper end of the sleeve.

4. A construction as defined in claim 1, and water effervescent material mixed with the water soluble dye.
